UNITED STATES PATENT OFFICE.

JOHN P. RIDER, OF MATTEAWAN, NEW YORK.

DESIGN FOR AN INDIA-RUBBER RATTLE.

SPECIFICATION forming part of Design No. 16,481, dated January 19, 1886.

Application filed November 20, 1885. Serial No. 183,458. Term of patent 14 years.

To all whom it may concern:

Be it known that I, JOHN P. RIDER, of Matteawan, in the county of Dutchess and State of New York, have invented and produced a new, original, and useful Design, Shape, or Configuration for India-Rubber Rattles, which invention is fully set forth in the following specification.

The accompanying photograph represents a rattle made in accordance with my invention. The said photograph shows a rattle consisting of a bulb or ball, a straight portion or stem, and a ring at one end of the stem. The bulb or ball is ornamented with corrugations or flutings extending lengthwise or from the top to the bottom of this part of the rattle. These flutings or corrugations give to this part of the rattle a melon-like appearance, which is a

striking feature of the design. The ring and stem are also ornamented, as shown by lines. Those on the ring form a succession of scallops. Other suitable or appropriate ornamentation may, if desired, be adopted for this part of the rattle.

What I claim is—

The design for rattles herein shown and described, consisting of the ball or bulb ornamented with flutings or corrugations, the straight portion or stem, and the ring.

In testimony whereof I have signed this specification in the presence of two subscribing witnesses.

JNO. P. RIDER.
